UNITED STATES PATENT OFFICE.

FRANK J. GOODWIN, OF LEXINGTON, KENTUCKY.

VISE.

1,110,683.

Specification of Letters Patent. Patented Sept. 15, 1914.

Application filed July 1, 1914. Serial No. 848,391.

To all whom it may concern:

Be it known that I, FRANK J. GOODWIN, a citizen of the United States, residing at Lexington, in the county of Fayette and State of Kentucky, have invented a new and useful Vise, of which the following is a specification:

My invention relates to improvements in vises and more particularly to vises for filing or fine finishing work and consists in a vise adapted to be placed between the jaws of an ordinary vise such as is used by blacksmiths, machinists, coppersmiths or in fact almost any mechanic.

The object of this invention is to provide a vise of the character referred to which may be placed in a larger vise and is always open and ready for use.

Another object is to provide such a vise which will hold the work in a position so that it may be easily worked upon by a mechanic without necessitating his having to assume an unnatural position in order to perform his work.

A further object is to provide an article of the character referred to which will be durable and inexpensive to manufacture and easy to operate.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made without departing from the spirit or sacrificing any of the advantages of the invention.

In the accompanying drawings: Figure 1 is a side elevation of a common form of bench vise showing my improved vise placed therein. Fig. 2 is a similar view on a smaller scale showing my vise placed in position in a blacksmiths vise. Fig. 3 is a longitudinal section through my vise on an enlarged scale.

Similar numerals of reference indicate corresponding parts throughout the several figures of the drawings.

The numerals 1 and 2 indicate the stationary and movable jaws respectively of a common form of bench vise in which is shown my improved finishing vise.

My vise comprises an upper jaw and a lower jaw 3 being provided

with a downwardly disposed arm 4 at the lower extremity of which is formed a reduced head 5 provided with an inclined slot 6. A lug 7 is formed upon the arm 4 at a point adjacent to the jaw 3, said lug being adapted at all times to rest upon one of the jaws of a common form of vise thus supporting my vise between the jaws of the larger vise as shown in Figs. 1 and 2 of the drawings. The arm 4 is provided upon its inner face with a recess 8, in which is pivoted by means of the pin 9 a connecting link 10 connected to the upper jaw as will be hereinafter described. A leaf spring 11 is located within the recess 8 and connected to the arm 4 by rivets or their equivalents 12, the upper curved end of the spring 13 bearing against the link 10 and tending to hold the jaws apart. The upper jaw 14 is provided with a downwardly disposed arm 15, the lower extremity of which is bifurcated as shown at 16 to receive the reduced head 5 upon the arm 4, a pin 17 being provided within the bifurcated portion 16, said pin being located within the slot 6 to limit the movement of the jaws. A lug 18, similar to the lug 7, is provided upon the arm 15. A recess 19 is formed in the arm 15 to accommodate the lower extremity of the link 10, said link being pivoted within said recess by means of a pin 20.

The operation of this device is as follows: The vise is first set into a larger vise of some common form such as shown in Figs. 1 and 2, the lug 7 supporting the vise within the jaws of the larger vise. When work is placed between the jaws 3 and 14 and the larger vise is tightened, the jaw 14 will move downward toward the jaw 3, said jaw 14 being guided by means of the pin 17 traveling in the slot 6, the link 10 binding the two jaws together. As the jaw 14 is brought down toward the jaw 3 the lug 18 upon the arm 15 will come to rest upon the top of one of the jaws of the larger vise thus supporting the entire finishing vise within the jaws of the large vise by means of the lugs 7 and 18. When the movable jaw upon the large vise is released the spring 11 will cause the jaws of the finishing vise to open thus leaving the vise always open and ready for new work to be inserted between the jaws thereof.

This vise is especially designed for blacksmiths or machinists and has an advantage over the common type of vise in that the work clamped within this vise is brought

down flat before the mechanic who is working thereon so that he is better able to work and better able to see just what he is doing with the work held in this position. Especially for the blacksmith, is this device handy, where he is filing a bevel or roll upon iron or shoes as the work is held in such a position that he can see at all times the size bevel or roll which he is filing without having to assume an uncomfortable and unnatural position in order to accomplish his work.

Although the drawings and above specifications disclose the best mode in which I have contemplated embodying my invention I desire to be not limited to the details of such disclosure, for, in the further practical application of my invention, many changes in form and construction may be made, as circumstances require or experience suggests, without departing from the spirit of the invention, within the scope of the appended claims.

I claim:

25 1. A finishing vise adapted to be held between the jaws of a common vise and comprising a lower jaw and an upper jaw adapted to be moved toward each other, a link pivotally connecting both of said jaws

and a spring adapted to normally hold said jaws apart.

2. A finishing vise adapted to be held between the jaws of a common vise and comprising an upper jaw and a lower jaw, one of said jaws provided with an inclined slot, 35 a pin carried by the other of said jaws and located within said inclined slot, a link pivotally connecting said vise and a spring adapted to normally hold said jaws apart.

3. A finishing vise adapted to be held between the jaws of a common vise and comprising an upper jaw and a lower jaw adapted to be moved toward each other, one of said jaws provided with an arm having an inclined slot therein, the other of said vises provided with an arm carrying a pin, said pin located within said inclined slot, a link pivotally connecting said arms and a spring carried by one of said arms and bearing against said link to normally hold 50 said jaws apart.

In testimony that I claim the above, I have hereunto subscribed my name in the presence of two witnesses.

FRANK J. GOODWIN.
